UNITED STATES PATENT OFFICE.

ELI T. STARR, OF PHILADELPHIA, PENNSYLVANIA, ASSIGNOR OF ONE-HALF TO WM. J. PEYTON, OF WASHINGTON, D. C.

SYSTEM FOR UTILIZING TIME-SWITCHES FOR ELECTRIC CIRCUITS.

SPECIFICATION forming part of Letters Patent No. 269,476, dated December 19, 1882.

Application filed November 13, 1882. (No model.)

To all whom it may concern:

Be it known that I, ELI T. STARR, of the city and county of Philadelphia, in the State of Pennsylvania, have invented certain new and useful Improvements in Systems for Utilizing Time-Switches for Electric Circuits, of which the following is a specification.

My invention relates more particularly to a system of distributing electrical energy or power from a generator or generators by means of automatic or time switches, whereby an electric current or currents may be automatically directed to and cut off from apparatus to be acted upon or worked by the current or currents at predetermined times.

The subject-matter claimed herein is distinctly pointed out at the close of the specification, while the objects and some of the capabilities of my invention will also hereinafter sufficiently appear.

The accompanying drawings illustrate my improvements as embodied and organized in the best way now known to me.

Some of my said improvements may be used without the others and in ways differing from that particularly shown in said drawings.

In said drawings, Figure 1 is a diagram showing an organization of my improvements, there being illustrated two sets of apparatus to be worked by the current of the main or charging line, with their respective automatic switches to throw them into and cut them out of said line, or a branch thereof, at predetermined times, there being also depicted in said figure other apparatus to be worked by the main current when desired, said last-mentioned apparatus being thrown into and cut out of action at will by means of an independent circuit, including electro-magnetic switch devices. Fig. 2 is a view on a larger scale than that of Fig. 1 of the automatic switch arrangement and portions of the circuit-connections, with the apparatus to be acted upon or operated by the current of the main line. Fig. 3 is a detached view of the setting device of the automatic switch on a still larger scale than that of Fig. 2, and Fig. 4 is a section through said device and through a portion of the clock-work mechanism on the line 4 4 of Fig. 2. Fig. 5 is a diagram illustrating the

switch for throwing the apparatus into and cutting it out of the main circuit as controlled by electro-magnetic clock-work operated by a clock at a central station, an independent line being run from said last-mentioned clock, and a suitable generator of electricity at the main or charging station to the clock-work of the switch or switches. Fig. 6 is a diagram somewhat similar to that of Fig. 1, with the apparatus to be worked by the current of the generator or generators arranged in branches of the main line; and Fig. 7 is a view showing a modification of the devices depicted in Fig. 3.

A generator or generators of electricity, A, (preferably a dynamo or magneto electric machine or machines,) is shown as organized to throw current upon a main line, B, in which, or in branches thereof, are included the apparatus C to be acted upon or worked by the current of said generator. This apparatus C to be acted upon by the current is shown as consisting of a secondary battery or accumulator of electricity, which is to be charged from the main-line or charging current, and then cut out to constitute an independent source of electricity, so as to work, when required, electrical apparatus included in the working-circuit of said battery.

In order to automatically throw said secondary battery or electric accumulator C into the charging-circuit and automatically cut it out at predetermined times, I provide said circuit with a switch, D, which when in one position directs the current through the battery, while when in another position it deflects or carries the current around said battery, so as to have no effect thereon. The position of said switch D is determined by clock-work mechanism E, which may be set or adjusted to throw the battery into the charging-circuit at the time desired and cut it out of said circuit after submitting it to the charging operation for a requisite time. Said switch D preferably consists of a conducting lever pivoted to a suitable support at one end—for instance, upon the clock face or frame—by an insulated pivotal connection, e, the said pivoted end of the lever being electrically connected with the charging-line, so as to constitute the switch a part of the charging-circuit. Said lever-switch 100

extends, in the present example, across the face of the controlling clock-work E thereof, and its weight causes it to rest lightly upon the periphery of the setting-device F of said clock-work, which device, by determining the position of said switch around the pivot, determines whether the current shall be conducted through or directed around the battery, the range of movement of the switch-lever being limited by contact pieces or points g g' , forming part of the circuit-connections. Said contact pieces or points g g' may be mounted, as shown in Fig. 2, upon an upright support, G, the said contact-pieces being independently insulated.

The setting device F preferably consists of a main wheel or disk, f , having, say, one half of its periphery of less diameter than the other, as shown (partially by dotted lines) in Figs. 3 and 7, and of another wheel, f' , of similar construction, fitted to turn around a hub, f^2 , of said main wheel f , said last-mentioned wheel, f' , being mounted by friction, for instance, upon the tubular spindle or arbor H of the hour-hand H' of the clock-work mechanism, so as to turn therewith while adjustable thereon, when necessary, as shown in Fig. 4. A semi-circular slot, f^3 , is formed in the wheel f' , concentric with its axis, and a set-screw, h , working through this slot into the main wheel f enables the two wheels of the setting device F to be adjusted circumferentially relatively to each other and fixed together, as desired. When the two wheels or disks f f' are adjusted so as to have their largest diameters or portions opposed it will be obvious that a wheel is presented the periphery of which is of substantially the same diameter throughout, while if adjusted so as to have the parts of largest diameter cross or overlap each other a recess or depression, a , in the periphery of the setting device is formed, as shown, for instance, in Fig. 3 and the other figures of the drawings. This interruption in the continuity of the periphery of largest diameter of the setting device F, or, in other words, the extent of the recess a , may be varied as desired, the limit in the example shown being to one-half of the periphery of the device, which maximum limitation, it will be readily understood, is equal to six hours, inasmuch as the setting device rotates with the hour-hand of the clock-work, as before stated.

I have stated that the weight of the switch-lever D causes it to rest lightly upon the periphery of the setting device. The lever is supported upon the setting device by an insulated inclined projection or tooth, d . As long as the switch-lever D, by its tooth d , rests upon the periphery of largest diameter of the setting device F, the outer or free end of said lever will be held up in contact with the contact piece or point g , forming part of the circuit-connections, whereby the current will be carried or directed around the secondary battery C, so as to have no effect upon said bat-

tery, which is thus consequently cut out. When, however, by the lapse of time and by the rotation of the setting device by the clock-work mechanism, the predetermined space or depression a in the largest diameter of said setting device arrives opposite the tooth d of the lever D, said tooth will drop quickly down into said recess, and will cause the lever to break contact with the contact-point g and make contact with the contact-point g' , whereby the charging-current will be directed through the battery C to charge it, and the said battery will be continued in the charging-circuit until, by the rotation of the setting device with the clock-work, the shoulder f^4 of said device comes against the inclined face of the tooth d and gradually wedges or forces it outward, thus separating the lever from the contact-point g' and again making contact with the contact-point g . The battery will thus be cut out of the charging-circuit, and will constitute an independent source of electricity to work, when desired, electrical apparatus—such as lamps and motors, for example—which are included in the working-circuit C' of the battery.

The length of time the battery or other apparatus C remains in the charging-circuit or subject to the action of the main current will of course be determined by the extent of the recess or depression a of the setting device, and this may be varied by adjustment, as before described, while the period at which said apparatus is put into the circuit to be acted upon may be determined by adjusting said setting device by its frictional or equivalent connection around the spindle or shaft of the clock-work mechanism which carries it.

In order that the make and break or change of the circuit in throwing in and cutting out the apparatus C may be practically simultaneous, or the make effected with one contact-point just before the break with the other, so as to avoid sparks, which would occur on breaking from one contact before making with another, I construct the contact pieces or points g g' in the form of plungers surrounded by light or weak springs, as shown in Fig. 2. The plungers have a range of movement endwise in their guides or boxes sufficient to enable them to follow the lever-switch in its movements for a limited distance. Said lever in its movement thus makes contact with the opposite contact-point just before breaking contact with the point with which it has been in contact, and from which it is to be separated. The current is thus shifted from one contact-point to the other without an actual break of the circuit. The weight of the lever, after the lever has been shifted from the contact-point g to the contact-point g' , depresses said point g' , and thereby carries the lever away from said point g to direct the current wholly through the point g' , while when said lever in moving upward under the action of the setting device F has made contact with the

point *g* its contact with *g'* is then broken by the continued upward movement due to the continuation of the wedging or lifting action of said setting device and the yielding or end-wise movement of said contact-point *g*.

In order to lessen friction between the tooth *d* of the lever *D* and the setting device *F*, said tooth may be provided with a friction-roller, as shown in Fig. 7.

10 The working circuit or circuits *C'* of the battery *C* are provided with a switch or switches, *e*, by which to make and break said circuit or circuits, as desired.

15 It will be noticed that I have shown the clock-work mechanism *E* and switch *D* as mounted on the battery-vessel; but of course this is not necessary, though in some cases it is preferable. I have not shown the gearing and other internal connections of the clock-work, 20 as that is unnecessary. Any suitable form of clock-work in common use may be employed to rotate the hands and the setting device, and are preferably such as are capable of running for a long time—say a week or more—when once wound up.

25 In Fig. 1 I have shown the main circuit as organized for charging two secondary batteries—the one at the right of the figure to be charged between the hours of six and seven 30 o'clock and the one at the left hand to be charged between the hours of seven and eight o'clock; or, in other words, when the first battery is charged and cut out, the next battery is thrown in to be charged in turn. In practice, 35 in electric lighting in cities, for example, there will be a large number or series of separate batteries having independent working-circuits *C'* in one district (into a number of which districts the city will be divided) to be charged 40 simultaneously at one hour or other length of time, another large number or series in another district to be charged during the next hour or length of time desired, and so on, whereby it will readily be understood that I may utilize 45 a comparatively small generator or small number of generators to charge a vast number of secondary batteries, inasmuch as but a comparatively small number of the batteries will be charged at one time, the operation of cutting out and throwing in the batteries in succession or order being accomplished automatically, as before fully described. Each house to be lighted will preferably be provided with 50 a secondary battery or set of batteries provided with an independent working-circuit, while the charging-circuit or its branch at each house will be provided with a cut-out switch, *I*, whereby any one or more of the batteries and the apparatus worked by it may be cut out of 55 the main-line or charging circuit, when desired, for an indefinite period without cutting out or affecting the others. The dotted lines in Fig. 1 show the cut-out switch of one of the batteries in the position to cut out its respective 60 battery.

65 If one or more of the batteries or sets of bat-

teries in any district or series is of greater capacity or requires longer time to be fully charged than the others, the setting device or devices will of course be adjusted to keep said 70 battery or batteries in the charging-circuit for the time required, it being understood that each battery or set of batteries of each series or district is independent of the others in the same series or district, and may be charged for 75 a greater or less time.

I have particularly described secondary batteries as the apparatus to be affected by the current of the main line; but it will be obvious that in distributing electrical energy as a source 80 of power the apparatus *C* may, for instance, be electric motors to be automatically thrown into and cut out of the main circuit or its branches at fixed times. For example, the motors may be thrown into the main circuit during the usual working-hours of the mechanic during the day and then cut out, while the current of the generator may be utilized to run other apparatus during the remaining hours of the daylight and during the succeeding night. 90

In some instances, as for electric lighting with secondary batteries, it will be desirable to throw the batteries or apparatus *C* into the main or charging circuit but once only during the twenty-four hours of the day, instead of 95 once during every twelve hours, so that the batteries, for instance, may be charged during the daylight, and then cut out to constitute sources for running electric lamps at night. In these instances I prefer that the clock-face 100 be graduated to show twenty-four hours instead of twelve, as is usual, with the hands and the setting device of the switch organized correspondently, so as to make but one revolution in twenty-four hours. The change is so 105 obvious and may be accomplished in so many different ways as to need no illustration.

Instead of employing clock-work to be wound up by hand to control the switch or switches *D*, I may, and preferably in some instances do, 110 employ an electro-magnetic clock or clocks to control said switches. Said clock or clocks are included in an independent circuit, *J*, and their movements are governed by a clock, *K*, and battery or generator *L*, also included in 115 said circuit and located, for instance, at the central or charging station. Such an organization is shown in Fig. 5, and it is advantageous, in that it avoids the necessity of separately winding up each of the clocks in each district, 120 for example, which clocks may be very numerous and some of them widely separated.

By the electro-magnetic clock system I have described all the switch-controlling clocks in one or more districts may be run and controlled 125 in their movements from a central station. The clock-circuit *J* is provided with a switch, *j*, by which said circuit may be made and broken. Running or controlling one or a series of separate electro-magnetic clocks from 130 a distant point or central station is very common, and may be accomplished in many ways.

I therefore do not show the details of construction of such clock-work nor describe them, as such description would extend this specification to an unnecessary length.

In order to afford a ready means of utilizing the current of the generator or generators A, either while it is employed to work the apparatus C or after said apparatus shall have been cut out—as, for instance, at night, when the 10 apparatus is a secondary battery or batteries and they have been cut out—I include in the main circuit, or in a branch or branches thereof, an armature lever or levers, M, the upper or outer ends of which, when the said levers 15 are in their normal position, rest against contact-points 1, thereby directing the current along the main line without affecting the apparatus N, which may be electric lamps, for instance, for street-lighting purposes. The 20 said armature-levers are maintained in their said normal position in contact with the contact-points 1 by means of the springs m. When the current of the main line is to be directed to the said lamps N—at night, for instance, 25 when the batteries, having been charged during daylight, are cut out—the electro-magnets O, included in an independent circuit, P, are excited by closing said circuit by means, for example, of the switch Q, (leading from 30 a suitable battery or conducting off a portion of the current of the generator A,) whereby the armature-switches will be attracted by the magnets and will be caused to make contact with the contact-points 2. The current of 35 the main line will thus obviously be directed through the lamps N, and said lamps will continue to be supplied with current as long as the independent circuit P remains closed. As soon as said circuit is broken the magnets 40 will be no longer excited, the armature-switches will be released, and said switches will be thrown back to make contact with the contact-points 1, thus cutting the lamps N out of the main circuit.

45 The organization of the lamps N to be run directly by the charging or main current and thrown into and out of action from a central or charging station is shown in Figs. 1 and 6. The advantages of such an organization are 50 obvious. At each apparatus N the circuit is provided with a cut-out switch, n, whereby any one of the said apparatuses may be cut out when desired without affecting the flow of current along the line.

In Fig. 6 I have shown both the apparatus G and the apparatus N as arranged in branch circuits. The method of running the circuits is so clearly shown as to need no description. By opening the switch b² the circuit through 55 the branches is broken. It is to be understood, however, that other organizations of

branches and switches may be employed without departure from my invention.

Before reciting what I claim herein, it is proper to say that this application is restricted 65 to the three combinations herein-after set forth. This present application is a division of my application filed June 15, 1882, No. 64,244, and I wish it to be distinctly understood that I reserve the right to claim in my said application 70 of June 15, 1882, or in such other applications as I may elect to file, all the patentable subject-matter herein shown or described or substantially indicated, save that specifically recited in the three following clauses of claim. 75

I claim herein—

1. The combination of a switch forming part of an electric circuit, an apparatus to be acted upon by the electric current, and automatic mechanism acting by direct mechanical action 80 upon said switch so as to direct the current through or around said apparatus, (in contradistinction to acting through an electric circuit,) said automatic mechanism being provided with an adjustable setting device, substantially 85 as described, and with an adjustable connection between said device and the shaft of said automatic mechanism which carries it, the combination being and acting substantially as described, whereby the apparatus to be acted 90 upon by the current is automatically inserted in and withdrawn from the circuit by direct-acting mechanism, while the period at which said apparatus is put into the circuit to be acted upon, as well as the time the apparatus 95 remains subject to the action of the current, may be varied.

2. The combination, substantially as herein-before set forth, of a switch forming part of an electric circuit, an electric clock to control 100 said switch, a clock to control said switch-controlling clock, and an independent circuit including said clocks and a generator of electricity.

3. The combination, substantially as herein-before set forth, of a generator of electricity, a circuit to conduct the current of said generator, a series of independent electrical apparatuses to be worked by said current, a series of switches to control the admission of said 105 apparatuses to said circuit, a series of electric clocks to control said switches, a clock at a central station to control said switch-controlling clocks, and an independent circuit including said clocks and a source of electricity. 110

In testimony whereof I have hereunto subscribed my name this 9th day of November, A. D. 1882.
